William J. Beniston

INVENTOR

UNITED STATES PATENT OFFICE

95,010

DESIGN FOR A KNITTED TEXTILE FABRIC

William J. Beniston, Brooklyn, N. Y.

Application February 6, 1935, Serial No. 55,257

Term of patent 3½ years

To all whom it may concern:

Be it known that I, William J. Beniston, a citizen of the United States of America, residing in Brooklyn, county of Kings, and State of New York, have invented a new, original, and ornamental Design for a Knitted Textile Fabric, of which the following is a specification, reference being had to the accompanying drawing, forming part thereof, wherein, the figure is a plan view of a piece of knitted textile fabric, showing my new design.

I claim:

The ornamental design for a knitted textile fabric, substantially as shown.

WILLIAM J. BENISTON.
